UNITED STATES PATENT OFFICE.

ABRAHAM WOLFSON, OF NEW YORK, N. Y.

DESIGN FOR A LAMP-VASE AND LAMP.

SPECIFICATION forming part of Design No. 24,904, dated November 19, 1895.

Application filed August 26, 1895. Serial No. 560,607. Term of patent 3½ years.

To all whom it may concern:

Be it known that I, ABRAHAM WOLFSON, a citizen of the United States, residing at the city of New York, in the county of New York, State of New York, have invented and produced a new and original Design for Lamp-Vases and Lamps, of which the following is a specification, reference being had to the accompanying drawing, forming a part thereof, which represents a side elevation of my design.

The leading features of my design consist in the vase A, having the enlarged base B, the contracted top or neck C, and the reservoir D, connected with the neck C and provided with the flaring base E and the cap F.

The lower portion of the base B is provided with legs b, and said legs and the lower portion of the base are ornamented as herein shown, while the upper part of the base is gradually contracted to form the neck b², the gradually-contracted portion being provided with annular steps or shoulders b³.

The neck C is provided with an outwardly-directed annular base flange or step C' and an outwardly-directed annular top rim C².

The flaring base E of the reservoir D extends outwardly beyond the top of the neck C, and the upper surface thereof is ornamented or provided with any desired ornamental configuration, as shown at e, and the cap F, which is designed to closely fit and cover the upper portion of the reservoir, is also ornamented

on its upper surface, as shown at f, and said cap is also provided with an upwardly-directed or projecting neck f², which constitutes the neck of the lamp and to which the burner is attached.

The reservoir D is bowl-shaped in form, and the vase A substantially the shape of an inverted cone, the upwardly-directed base being inwardly contracted, as shown at a, and provided with downwardly-directed ornamental figures a', and the lower portion or apex of the cone is also provided with upwardly-directed ornamental figures a². The vase A is also provided with an annular ring or band a³.

The entire design is ornamental and pleasing in appearance, the outlines thereof being regular in form and the proportions being such as to produce the best possible effect.

Having fully described my new and original design, what I claim, and desire to secure by Letters Patent, is—

The design for lamp vase and lamp, as herein shown and described.

In testimony that I claim the foregoing as my invention I hereunto sign my name, in the presence of two witnesses, this 15th day of August, 1895.

ABRAHAM WOLFSON.
